DESIGN FOR A JEWELRY FINDING

Alfred Philippe, New York, N. Y.

Application January 12, 1942, Serial No. 105,140

Term of patent 3½ years

To all whom it may concern:

Be it known that I, Alfred Philippe, a citizen of the United States of America, residing in the city of New York, county of New York, and State of New York, have invented a new, original, and ornamental Design for a Jewelry Finding, of which the following is a specification, reference being had to the accompanying drawing, forming part thereof.

Fig. 1 is a plan view of a jewelry finding showing my new design.

Fig. 2 is an edge view thereof.

I claim:

The ornamental design for a jewelry finding, substantially as shown.

ALFRED PHILIPPE.
